(57) **CLAIM**

The ornamental design for an oral irrigator, as shown and described.

DESCRIPTION

FIG. 1 is a top, front, left side perspective view of an oral irrigator showing our new design;

FIG. 2 is a top, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings depict portions of the oral irrigator that form no part of the claimed design.

1 Claim, 8 Drawing Sheets
